UNITED STATES PATENT OFFICE

WILLIAM R. HUTTINGER, OF PHILADELPHIA, PENNSYLVANIA

HIGH VOLTAGE SWITCH

Application filed May 15, 1929. Serial No. 363,388.

I have invented an improvement in electric switches, and particularly an electric switch for use with high voltage installations, such as transmission lines and electrical devices 5 associated therewith.

An object of the invention is to provide a switch designed for successful and efficient operation at the highest voltages now transmitted.

10 Another object of the invention is to provide an electric switch having stationary parts enclosed in a suitable housing, and a cooperating movable member so supported as to be shiftable bodily to move its extremity 15 into and out of the housing through an aperture in the wall thereof, to engage and disengage one or more of said fixed parts as the circuit in which the switch is placed is to be closed or opened; said member also being 20 mounted so that it can be swung on a pivot to carry it away from the housing to full open position.

A further object of the invention is to provide a switch that is of light but strong construction, and certain and reliable in operation under all practical conditions.

With these and other objects and advantages in view, as will appear in the description that follows, the invention consists in 30 the novel features and combinations of parts that are herein set forth and defined in the appended claims. But I do not desire to be restricted to the exact details of construction that are actually illustrated herein; and 35 I reserve the right to make changes in shape, size, arrangement of the various elements and other details, which fall within the principle of the invention and do not exceed its scope.

On the drawings:

40 Figure 1 is a top plan of a switch according to my invention;

Figure 2 is a side elevation thereof; and

45 Figure 3 is a similar view of a portion and the switch showing how the movable member thereof is mounted and actuated.

On the drawings, the same numerals identify the same parts throughout.

The switch of this application is in a measure similar to that covered by my Patent 50 No. 1,685,087, granted Sept. 18, 1928, dis-

closing a movable switch arm cooperating with one or more fixed contacts in a suitable housing, which encloses and protects the latter. The main switch arm of that patent carries at one end a pivoted element 55 that is actuated to enter the housing and engage the contacts when said member carries said element into proper position. The operation of this element, however, requires a long movable rod or the like on the switch member, and the element and other parts of the switch must further be accurately mounted so that said element will infallibly pass through the entrance to the housing to the interior thereof. Thus the number of 60 parts is enlarged and the cost of manufacture increased. As switches of this type are intended for use in the open air, and as the conductors which the switch is to connect and disconnect are always placed some distance apart, necessitating a movable switch member of considerable length to open and close the circuit, it is important not only that the fixed parts be well encased and screened, but also that the switch shall embrace as 65 few parts as possible, with said parts arranged so that, when the movable member is operated, the penetration of the housing and the engagement of the fixed contacts is 70 insured. These objects are gained in the practice of this invention, by causing the end of the main switch member to enter the housing and make contact directly with the fixed parts, and by mounting this member so 75 that it can be first swung on a pivot into alignment with the entrance to the housing and then shifted longitudinally to impel its end into the housing as far as necessary. The movable switch member is thus made of 80 one piece, rigid from end to end, and carries no movable elements liable to become 85 loose with wear, or otherwise get out of order or function in a defective manner.

In the particular description of the drawings, I use the numeral 1 to indicate the movable arm or member of the switch which is 90 of some length and mounted so that it can both rotate about an axis at one end to lift it; and be shifted bodily in a longitudinal 95 direction, to carry its free extremity into a 100

housing 2 containing one or more fixed contacts 3, to be engaged by the end of the switch arm 1 when the circuit containing the switch is to be closed. The member may be constructed in any suitable manner and be tapered from the end which is mounted toward the opposite or free end to the required extent. It can be conveniently made of sections of tubing of successively smaller diameters and lengths. It carries one of the high-tension conductors 4, which runs along the arm 1 and is attached to the extremity which enters the housing 2. The entire structure of the switch is mounted upon a suitable support in the form of a horizontal beam 5, upon which rest the insulating column 6 carrying the housing 3 and other insulating columns 7 and 8 which mount the parts for supporting and operating the member 1. The column 7 is usually rotatable and the column 8 fixed; and these columns 6, 7 and 8 may be of any suitable construction or material. Further, the beam 5 may be secured to one of the towers of the transmission line or carried by any suitable part of the framework at the end of the transmission line; where the voltage of the line is stepped down and distributed to points where it is consumed. The insulating columns 6, 7 and 8 may rest at their bases on foot plates 9 attached to the top of the beam 5.

On the upper end of the insulating column 8 is a casting 10 comprising a casing 11 in the ends of which are bearings for a shaft 12. The extremities of this shaft project from the opposite ends of the casing 11 and carry fixed crank arms 13. The adjacent extremity of the member 1 is shaped to provide a yoke 14, the arms of which extend laterally from the member in an upward direction and are secured to the ends of the cranks 13 by pins 15. Obviously, with this construction, when the arm 1 is in the position shown in broken lines on Fig. 3, the turning of the shaft 12 will raise or lower the member 1; but if the member 1 is elevated and is then dropped to a horizontal position, further movement of the arms 13 will cause lengthwise movement only of the switch member 1. If the shaft 12 is now rotated in the reverse direction, the member 1 will first be pulled back until the arms 14 reach the ends of the shaft 12 and then the member 1 can be lifted. Thus the free extremity of the switch arm can be withdrawn from the housing 2 and the member 1 swung upward. The extremity of the member 1 carrying the yoke 14 has projections 16 which engage beneath the ends of the shaft 12 during the lifting or lowering movement of the member 1.

The casing 11 has a hollow projection 17 in which is a worm 18. This worm engages a gear-wheel 19, fixed to the shaft 12 in the casing 11, both the worm and the gear wheel 19 being shown in broken lines in Fig. 3. The

worm is mounted upon the end of the vertical rod 20 which extends downwardly to the column 7 and is fixed thereto. This column is rotated from its lower end by bevelled gear 21 which engages a similar bevelled gear 22. A third bevelled gear 23 on the end of an operating rod 24 meshes with the gear 22. The gears 21 and 23 may be horizontal and the gear 22 vertical so that when the shaft 24 is turned, it will act through the gears 23, 22 and 21 to rotate the column 7. At 25 is indicated a suitable U-shaped bearing attached to the bottom of the beam 5, the end of this bearing being presented to the observer and being vertical and the arms thereof extending away from the observer and being horizontal to mount gears 21, 22 and 23; one of the horizontal arms of this bearing being secured to the bottom of the beam 5. The gear 21 is of course rigid with the lower end of the column 7, and the manner in which this column is rotatably mounted on the beam 5 is well known and need not be further described. The beam 5 may consist of two separate parallel members, and the plate 9 at the lower end of the column 7 may support a suitable thrust bearing for the column 7, and through this bearing the connection between the column and the gear 21 extends.

The casing 10 is provided with arms 26 to 29 the lower ends of which are attached a ring 27 encircling the tops of the insulators 7 and 8. A similar ring 28 encircles the top of the insulating column 6 and is supported by similar arms 27 from the casting 29 which comprises the housing 3. This housing is closed on the top, bottom and sides and at one end, but at the opposite end it has an opening to give entrance to the extremity 30 of the switch member 1. The casing 29 also carries a guide 31 in front of the aperture leading to the exterior of the housing 3, the guide being in the form of an upright projection with a notch opening upward so that when the member 1 drops, this extremity 30 first engages the notch of this guide to align the member 1 with the opening in the housing 2. Then on the longitudinal movement of the arm 1, the extremity 30 slides easily and surely into the housing and makes contact with the fixed parts indicated at 3 therein. These fixed parts are, of course, connected to the opposite side of the circuit of the switch and the conductor 4 may be secured at points along the length of the switch arm 1 by supporting elements 32.

When the switch is open, the arm 1, yoke 14 and crank arms 13 will occupy the position shown in dot-and-dash lines on Fig. 3, with the projections 16 engaging the ends of the shaft 12. The lower end of the shaft 24 will be secured against movement until the closing of the switch is necessary, and then movement of this shaft will be transmitted to the gears 23, 22 and 21 to turn the column 7.

7 and shaft 20 and the gearing 18 and 19 in the casing 11 to operate the shaft 12 and lower the member 1, the arms 13 and 14 now moving as a unit. When, however, the extremity 30 of the arm 1 has dropped into the notch of the guide 31, further rotation of the crank arms 13 will shift the member 1 away from the shaft 12 and force the extremity 30 into the housing 2. To open the switch, the shaft 12 is caused to move in the opposite direction; whereupon the arms 13 first pull upon the arms 14 of the member 1 to draw the end 30 out of the housing 2. This longitudinal shifting of the member 1 continues until the ends of the shaft 12 make contact with the arms 14; and the member 1 will then be supported at one end by connection with the crank arms 13 and at its other end by the guide 31, with the extremity 30 of member 1 clear of the housing 2. Further rotation of the shaft 12 now lifts the member 1 as indicated in Fig. 3.

The member 1 is thus not only securely mounted and certain in operation but also requires no movable parts to be disposed upon it. The closing of the circuit is assured and the housing 2 can be made in one piece.

The housing 2 will be sufficient to screen the parts 3 to the extent required. The switch can be made of necessary size and strength and as it involves the smallest possible number of parts, the cost of manufacture can be kept within the desired limits.

Further the switch, according to this invention, is especially adapted for use upon transmission lines operating at very high voltages; and will operate with the greatest efficiency, both at opening and closing, reducing sparking to the minimum and thus avoiding damage to the switch. When the switch is closed, the extremity 30 is thrust into engagement with the fixed parts 3 quickly and when the switch is opened, parts 3 and 30 are separated in the same manner. The advantage of such a mode of operation will be quite apparent to those skilled in this art.

I claim:

1. A switch comprising a member having an arm extending laterally from one end, a shaft, an arm fixed to said shaft and pinned to the outer end of the first arm, and a projection extending from the opposite end of the first arm to engage said shaft so that said member can be both raised and lowered about said shaft as an axis and then shifted bodily away from said shaft.

2. A switch comprising a member having at one end a yoke, the arms of which extend laterally with respect to said member, a shaft, fixed arms mounted upon the shaft and pinned to the outer ends of the arms of said yoke, and projections carried by said yoke at the opposite ends of the arms thereof to engage the shaft when the arms on

said shaft and the arms on said yoke are substantially in coinciding relation, so that rotation of the shaft may both rotate said member about said shaft as an axis to raise and lower the member, and to shift said member longitudinally away from said shaft.

3. A switch comprising a casting, an insulating column for said casting, the latter comprising a housing, fixed contact parts in the housing, the casting also comprising an upright guide having a notch therein open at its upper end adjacent the housing and said fixed parts therein, a switch member, one extremity of which is shaped to be received in said guide and to be thrust into the housing to engage said fixed parts, a casting and insulating supports therefor at the opposite extremity of said member, said casting including a casing having bearings for a shaft, the ends of the shaft projecting from the opposite ends of said casing, a gear in said casing on said shaft, gearing carried by one of said insulating supports for rotating said shaft, the adjacent extremity of said member having a yoke, the arms of which project laterally therefrom, arms fixed on said shaft and pinned to the arms of said yoke at their outer ends, and projections at the opposite ends of the arms of said yoke to engage said shaft to permit said member to be raised and lowered and shifted longitudinally to force the first-named extremity into and out of the housing.
